UNITED STATES PATENT OFFICE.

HARRISON D. FLEGEL, OF RACINE, WISCONSIN.

STILT.

1,264,047.

Specification of Letters Patent. Patented Apr. 23, 1918.

Application filed February 12, 1918. Serial No. 216,776.

To all whom it may concern:

Be it known that I, HARRISON D. FLEGEL, a citizen of the United States, and resident of Racine, in the county of Racine and State of Wisconsin, have invented certain new and useful Improvements in Stilts; and I do hereby declare that the following is a full, clear, and exact description thereof.

My invention relates to new and useful improvements in stilts, more particularly to that type in which the stilt steps are adjustable to vary their distance above the ground.

Although there are at present stilts which have adjustable steps, yet in moving the same it is necessary for the user to dismount in order to raise or lower the same. It is the principal object of the present invention to provide an adjustable stilt step with means whereby the same may be adjusted 20 upwardly while in use, or in other words without the necessity of the user dismounting.

An additional object is to provide a simply constructed stilt which can be inexpensively manufactured and marketed, and one which will be very efficient in operation.

With these and other objects in view which will become apparent as the description proceeds, the invention resides in certain novel features of construction, combination and arrangement of parts which will be hereinafter more particularly described and claimed and shown in the drawing, wherein:

Figure 1 represents an elevational view of 35 a portion of a pair of stilts constructed in accordance with my invention.

Fig. 2 is an inner elevational view of a portion of one of the stilts.

Fig. 3 is a horizontal transverse sectional view on the line 3—3 of Fig. 2, and

Fig. 4 is a similar view on the line 4—4 of the same figure.

Inasmuch as both of the stilts are constructed substantially alike, one only will be 45 particularly described. In the accompanying drawing similar reference characters designate like parts throughout the different views.

Referring more particularly to these several views it will be seen that the numeral 1 denotes a stilt staff or standard upon which an adjustable step 2 is adapted to slide. The standard 1 is preferably of wood, while in order to reduce the size and decrease the cost 55 of the metal parts, such as the step 2, an elongated plate or bar 3 is secured to and

spaced from the inner face of said standard by means of spacing blocks 4 and screws 5.

The plate 3 is adapted to slidably receive the stilt step 2, said step being preferably formed from a plate of sheet metal bent into substantially U-shape, one arm 6 of which forms the step proper and receives the weight of the user, the other arm 7 being relatively short and adapted to provide a 60 foot piece, the purpose of the same being hereinafter more particularly set forth. Each of the arms 6 and 7 adjacent their connection with the base portion 8 of the U-shaped plate is provided with an elongated opening 9 substantially the same size and shape as the plate 3, said openings being aligned to receive said plate. As shown in Fig. 1 the base portion 8 is disposed in engagement with the inner surface of the plate 70 3, and the arms 6 and 7 project beyond the outer surface thereof. Said base portion 8 is provided with a longitudinally extending slot 10 connecting the openings 9 to permit the step to slide past the spacing blocks 4. 80

The step is supported and held in adjusted positions by means of a bracket which is in the form of a vertically positioned plate 11 which depends from and is secured to the arm 6. The edge of said 85 bracket adjacent the plate 3 is normally substantially parallel with the base portion 8 of the step, and at the lower end of this edge is formed an inwardly projecting stop 12, the lower edge of the same being at right 90 angles to the plate 3 and the upper edge at an oblique angle thereto. This stop 12 is designed to engage in any one of the longitudinally vertically disposed series of openings 13 in the plate 3, said series being 95 clearly shown in Fig. 2.

In the operation of my device, assuming that a person is standing on the steps of a pair of stilts as in Fig. 1 and desires to elevate the said steps, he alternately lifts his 100 feet from the arms 6 and into engagement with the foot pieces 7, such upward movement of the feet causing the stilt steps to be raised. During their upward movement the inclined edge of the stops 12 will permit the same to readily ride out of any of the openings 13. When, however, the upward movement ceases the spring action of the U-shaped member forming the foot-piece, especially at the junction of the arm 7 and 110 body portion 8, the stop will spring into the adjacent opening 13. When force is ap-

plied downwardly upon the arm 6 movement of the stilt step will be prevented by the engagement of the straight edge of the stop 12 with one of the openings 13. A 5 yoke 14 carried by the plate 11 embraces the plate 3 and prevents excessive movement of the former away from the latter.

Attention is directed to the fact that owing to the slotted base 8 projecting in 10 one direction from the foot-arm and the bracket 11 projecting in the opposite direction, lift of the foot to engage the rigid foot-piece 7 will cause a positive rock of the entire step and as the stop 12 will be drawn 15 out of its engaged notch, the entire step will readily lift upon the plate or bar without any tendency to cramp or become disarranged, as the power of the foot is applied by pressing inwardly and against the 20 foot-piece 7. When the weight of the person is put upon the foot-arm there is no tendency for the step to inadvertently slip because the weight will tend to force the stop 12 into engagement with the first notch 25 which it opposes. Thus the entire foot-step has a leverage action to insure locking, while, at the same time, it will not cramp by a foot lift.

From the foregoing description it will be 30 readily seen that a stilt constructed as illustrated in the drawing can readily be operated to permit upper movement of the stilt steps while the same are occupied. Various minor changes may be made in the form and 35 proportion of the several parts without departing from or sacrificing any of the features of the invention, for instance the elongated plates 3 may be eliminated and the stilt steps permitted to slide directly on the 40 standards 1.

I claim:—

1. A stilt comprising a metallic bar hav-

ing a series of recesses therein, a step in 45 slideable union with the bar, the step comprising a foot-arm, a slotted base-piece engageable with the bar, and a rigid foot-piece extending outwardly from the terminal of the base-piece constituting a lifting element, a bracket extending from the foot-arm in the opposite direction from the base 50 portion thereof and having a stop at its outer end adapted to engage the recesses in the aforesaid bar, a guide yoke associated with the stop and engageable with the bar.

2. A stilt comprising a metallic bar having 55 a series of recesses therein, a step in slideable union with the bar, the step comprising a foot-arm, a slotted base-piece engageable with the bar, and a rigid foot-piece extending outwardly from the terminal of the base-piece constituting a lifting element, a bracket extending from the foot-arm in the opposite direction from the base 60 portion thereof and having a stop at its outer end adapted to engage the recesses in 65 the aforesaid bar.

3. A stilt comprising a staff, a metallic bar provided with a series of recesses, secured to the staff and offset therefrom, a step in slideable union with the bar, the step 70 comprising a foot-arm, a slotted base-piece engageable with the bar and a rigid foot-piece extending outwardly from the terminal of the base-piece constituting a lifting element, and a bracket extending from the 75 foot-arm in the opposite direction from the base portion thereof and having a stop at its outer end adapted to engage the recesses in the aforesaid bar.

In testimony that I claim the foregoing I 80 have hereunto set my hand at Racine, in the county of Racine, and State of Wisconsin.

HARRISON D. FLEGEL.
